METHOD AND MACHINE FOR SURFACING TRACK TIES

Russell E. Paulson, 406 N. Maple Ave., Itasca, Ill.

Filed Feb. 26, 1957, Ser. No. 642,538

3 Claims. (Cl. 104—9)

My invention relates to a method and machine for surfacing track ties, and more particularly, to a method and machine for shifting and surfacing, or bringing up to grade, track ties after the track rails have been jacked to a new grade.

After a new track grade has been established and the track rails have been freed as necessary from the ties and have been jacked to the desired grade, it has been conventional practice to lift the track ties, from their former positions, up against the bottom or underside of the track rails and then push new ballast underneath the individual ties by hand or with a mechanical tamper.

Contrary to this conventional practice, it is a principal object of my invention to provide a track tie surfacing method and machine wherein tamping requirements are practically eliminated, or are at least substantially reduced, and wherein new ballast in most cases is not required.

A further object of my invention is to provide a track tie surfacing machine and method which materially reduces the man power required to do a job of this character.

Another object of the invention is to provide a track tie surfacing machine that will also remove a track tie laterally of the track.

Still another object of the invention is to provide a track tie surfacing machine that will shift track ties longitudinally of the track, that will straighten skewed ties, and that will rake the ballast at the center of the track where this is needed to insure that a tie does not bear on the ballast at the center of the track.

Yet a further object of the invention is to provide an improved track rail clamping device for track tie surfacing machines or the like.

Still a further object of the invention is to provide an improved tie gripper for track tie surfacing machines or the like.

Yet another object of the invention is to provide a track tie surfacing machine which is economical of manufacture, convenient in use, and readily adapted to a wide variety of track tie surfacing operations.

Other objects, uses, and advantages will be obvious or become apparent from a consideration of the following detailed description and the accompanying drawings.

In the drawings:

Figure 1 is a side elevational view of one embodiment of the invention, parts being shown in section, illustrating how track ties are handled in accordance with the principles of my invention;

Figure 1a is a diagrammatic view illustrating a hydraulic system that may be employed for operating the various rams forming a part of the machine shown in Figure 1;

Figure 2 is an end elevational view of the machine shown in Figure 1, taken from the right hand side of Figure 1, with parts broken away for clarity of illustration;

Figure 3 is a plan view of the machine shown in Figure 1, with parts broken away for clarity of illustration;

2

Figures 4 and 5 are fragmental end elevational views illustrating the operation of the rail clamping device employed in the machine of Figure 1;

Figure 6 is a fragmental end elevational view similar to Figures 4 and 5 illustrating a device for and the manner of moving a track tie laterally of the track in accordance with the principles of my invention;

Figure 6a is a plan view of the spud shown in Figure 6;

Figure 7 is a diagrammatic perspective view of the tie gripper platform and supporting members forming a part of the machine shown in Figure 1;

Figure 8 is a diagrammatic perspective view of one pair of tie grippers employed in the machine shown in Figure 1;

Figure 9 is a diagrammatic cross sectional view along line 9—9 of Figure 3;

Figure 10 is a diagrammatic elevational view of the rake member forming a part of the machine shown in Figure 1;

Figures 11 and 12 are diagrammatic sectional views illustrating a type of hydraulic fluid flow control valve that may be employed in the machine shown in Figure 1; and

Figure 13 is a diagrammatic plan view of the member on which the rake device is mounted, part of same being broken away.

GENERAL DESCRIPTION

Reference numeral 10 of Figures 1, 2, and 3 generally indicates one embodiment of a machine arranged in accordance with the principles of my invention, which includes a wheeled frame or truck 12, a pair of tie grippers 14, a pair of rail clamping devices 16, and a rake device 18 (see Figures 2 and 3). Generally speaking, the machine 10 is employed, after rails 22 have been raised to a new grade, to lift ties 20 upwardly against the underside of track rails 22 and shift them longitudinally of the track rails to the positions indicated at the left of Figure 1.

SPECIFIC DESCRIPTION

The truck or wheeled frame 12 generally comprises a pair of longitudinally extending channels 26 (see Figure 3) secured at their ends to transverse channels 28 as by welding or in any other suitable manner. Wheel axles 30 to which flanged wheels 32 are keyed or otherwise fixed are rotatably secured to beams 26 by an appropriate journaling structure 34. The wheeled frame or truck 12 carries a power unit 36, such as a gasoline motor, two tanks 38 for hydraulic fluid, pumps 40 on either side of the frame or truck 12 and driven by the motor 36 through belts or chains 42, and two valve banks 44 to which appropriate piping (not shown) extends from the pumps 40. Appropriate piping (not shown) also extends from the two valve banks 44 to the hydraulic rams about to be described.

THE TIE GRIPPERS

Along each side of the frame or truck 12 a pair of spaced longitudinally extending beams 50 are secured in place, as by welding them to suitable uprights 52 that are in turn welded to cross beams 28. A transversely extending beam 54 is secured to the ends of beams 50 at each end of the truck or frame by upright angle irons 55. Bracing channels 57 (see Figure 6) may also be secured to the ends of beams 50.

A tie gripper supporting structure such as that shown in Figure 7 is mounted between the spaced beams 50 on each side of the vehicle and outboard of said rails. The tie gripper supporting structure comprises a framework or platform 60 composed in the illustrated embodiment of spaced channels 62 secured together below by plates 64 and 66 and above by angle bars 68 and 70. These

elements may be secured together in any suitable manner, as by welding. Each framework or platform 60 includes a ram support plate 72 that is welded between the channels 62, a pair of opposed upright angle bars 74 that are fixed to adjacent channels 62 and fixedly carry abutment forming rods 75, and a brace channel member 76 secured between the angle bar 68, channels 62, and the tops of bars 74, in any suitable manner, as by welding.

Each framework or platform 60 slidably carries a supplemental framework or platform 80 (see Figure 7), which includes a plate 82 that is positioned below channel members 62, a pair of upright angle bars 84 that are secured to plate 82 and extend upwardly between members 62, abutment forming rods 85 carried by bars 84, a pair of triangular brace plates 86, braced by inclined plate 87, that are secured between the plate 82 and the respective angle bars 84, and a pair of angle bars 88 that are secured on either side of and between angle bars 84 and brace plates 86. The angle bars 88 are positioned above channel members 62. Thus, the supplemental framework or platform 80 is slidably mounted on the framework or platform 60 and plate 82 and angle members 88 serve as guiding and positioning elements for properly locating the supplemental platform or framework 80 with respect to the platform or framework 60.

The frameworks or platforms 60 and 80 each carry a tie engaging member of the types shown in Figure 8, the member 90 being carried by the platform 60 and the member 92 being carried by the platform 80. The members 90 and 92 in the illustrated embodiment each comprise a length of track rail that is shaved as at 94 to provide a tapering tie engaging end. The tie engaging ends of the members 90 and 92 are formed with projections 96 in any suitable manner, as by applying bead welding in spaced apart relation.

The member 90 at its upper end includes a pair of plates 100 secured to each side of the rail head 102 thereof and diverging outwardly from the head. This is done by welding the ends of the plates 100 to the web 104 of the member 90 (see Figure 3). Plates 106 and 107 are secured to the top and bottom edges of the plates 100 to provide a sort of housing for plates 108 welded to the rail head portion 102 of the member 92. As the ends of the plates 103 that are spaced from the member 92 are welded together, they converge in a direction away from the head 102 of the member 92 and thus are complementary to and fit inside the enclosure formed by the plates 106, 107, and 108. The bases 109 of the members 90 and 92 are received between the abutment forming rods and flanges of the respective upright angle bars 74 and 84 to mount them on their movable platforms (see Figure 3).

As shown in Figure 1, a hydraulic ram 110 is interposed between the plate 72 forming a part of framework or platform 60 and the plate 107 that is secured to the tie engaging member 90.

As best shown in Figure 2, the members 62 are received between truck or frame members 50 on each side of the vehicle. The ends of plates 64 and 66 and angle bars 68 and 70 extend over the respective beams 50 whereby the frames 60 are supported by the members 50.

The platforms 60 also include an abutment plate 112 to which one end of a hydraulic ram 114 is secured (see Figure 1). The other end of hydraulic ram 114 is secured to a plate 116 that is fixed to the ends of the beams 50 at one end of the vehicle. At the other end of the vehicle a hydraulic ram 118 is fixed in any suitable manner to and between a plate 120 (see Figure 1) fixed to the framework or platform 80 (between plates 86) and plate 66 of framework or platform 60.

Rams 110, 114, and 118 may be of any conventional type, but ordinarily include a cylinder 124 from which a piston rod 126 extends that is actuated by hydraulic fluid acting on an appropriate piston member of any conventional design.

THE RAIL CLAMPING DEVICES

The rail clamping devices 16 are best shown in Figures 3 and 4 through 6. One of these devices is secured to each end of the frame or truck 12 and since they are identical, only one will be described.

The rail clamp device 16 shown in Figures 4, 5, and 6 is the one at the right hand side of Figures 1 and 3. The devices 16 each comprise a pair of pendently mounted rail engaging gripping jaw forming bars or members 130 and 131 actuated by a hydraulic ram 132 carried by beam 54. The members 130 and 131 are positioned on either side of a track rail 22 and member 130 includes a toe or projection 130a. The member 131 is received between a pair of angle members 134 that are welded or otherwise fixed on angle member 133 that is fixed to the end beam 54. Angle members 135 fixed to the respective members 134 form outer guiding abutments for the member 131. The gripper member 130 is suspended in a trolley like structure 136 that in the illustrated embodiment comprises spaced vertical plates 138 secured together as by welding them to upper and lower spacing plates 140 on one side of the structure 136 and a pair of spaced bars 144 on the other side of the device. Studs or bolts 145 project outwardly of the outer plate 138 a short distance for a purpose hereinafter made clear. The beam 54 is received between the plates 140 and the inner pair of plates 138 while the member 130 is received between the bars 144. A pair of stops 147 are fixed to member 130 on either side thereof and are proportioned to extend over the adjacent plates 138.

A cam member 146 is secured to one of the angle members 134 and extends laterally across the member 130, on which is mounted a cam roller 150 that rests on the cam surface 152 of the member 146 when stops 147 are raised above structure 136. The structure 136 carries a cam plate 160 which is formed with a cam surface 162 on which rests a cam roller 164 carried by the member 131. The piston rod 165 of ram 132 is secured to the structure 136 in any suitable manner, such as the diagrammatically illustrated connection 163. For purposes of illustration, the ram 132 is shown secured to angle bracket 167, reinforced by the plate 169, carried by beam 54.

As shown in Figures 4 and 5, as ram 132 is operated to push structure 136 to the left, members 130 and 131 drop to the level of the track rail 22; member 130 is then pushed toward member 131 until the track rail is clamped by these members. When the piston rod 165 is retracted, the member 130 is separated from member 131, and both members then move upwardly to the positions of Figure 4. Toe or projection 130a of member 130 opposes vertical forces tending to draw the track rail from the device 16.

THE RAKE DEVICE

The rake device 18 is mounted adjacent the center of the truck or frame 12, and consequently, adjacent the center of the track bed. It includes a rake member 170 of the type diagrammatically illustrated in Figure 10 which is moved vertically by an appropriate hydraulic ram 172 mounted on a beam 174 that is carried by the platforms 60. As shown in Figures 2 and 13, the respective ends of beam 174 are secured to the inner channel members 62, of frameworks or platforms 60 by a bolt 176 passing through elongated slots 178 formed in the respective ends of beam 174. Of course, an appropriate nut 179 is secured to the end of bolt 176. Angle members 181 fixed to beam 174 guide the vertical movement of rake member 170.

The beam 174 is moved longitudinally of the track when platforms 60 are moved and slots 178 are provided to permit independent movement of the platforms 60 as hereinafter described.

THE HYDRAULIC SYSTEM FOR RAMS

The rams 110, 114, 118, 132, and 172 are preferably of the double acting type and are incorporated in a hydraulic circuit such as, or similar to, that diagrammatically illustrated in Figure 1a (in which the actual ram cylinders are not shown in interests of simplicity). As shown in Figure 1a, the valve banks 44 are arranged adjacent each other. Each valve bank in the illustrated embodiment is made up of five fluid flow control valves that may be of the type diagrammatically illustrated in Figures 11 and 12, one valve being provided for each cylinder. A conduit 194 extends between a tank 38 and a pump 40 for each valve bank, and a hydraulic conduit 196 extends between the pump 40 and a manifold distributing device 198 of any appropriate construction which feeds hydraulic fluid to the individual valves 200 of the respective valve banks. Hydraulic fluid passes from the individual valves 200 to appropriate fluid flow collecting devices 202 from which the hydraulic fluid passes through appropriate respective conduits 204 to return conduits 206 and thence to the respective tanks 38. Each valve bank controls a ram 110, 114, 118, and 132, and one of the banks controls ram 172. The extra valve 200 controls a propelling mechanism later described.

The valve 200 diagrammatically illustrated in Figures 11 and 12 (for illustrative purposes only) includes an appropriately formed plunger 210 which is moved back and forth inside the valve body by a handle 212 (see Figure 1) through any appropriate linkage mechanism (not shown). Conduits 214 and 216 extend to each end of the ram cylinder which is controlled by the illustrated valve 200 while the conduits 218 and 220 are connected to the diagrammatically illustrated distributing and collecting devices 198 and 202. When the plunger element 210 is in the position of Figure 11, hydraulic fluid under pressure enters the valve 200 from conduit 218 and passes into the conduit 214 that leads to one end of the hydraulic cylinder controlled by the valve, while hydraulic fluid leaves the other end of this hydraulic cylinder through conduit 216, thence through the valve 200 and into conduit 220. When the plunger element 210 is positioned as shown in Figure 12, the hydraulic flow from the valve is reversed. In the illustrated system, the pumps 40 will be of the type that include bypass or pressure release mechanisms that are brought into play on intermediate positions of valves 200, when there is no fluid flow through them.

As a practical matter, the actual hydraulic circuiting employed may be of any conventional type that insures that the individual rams can be independently actuated and that they are all double acting. The actual hydraulic fluid conduits and flow control valves employed may be of any conventional type and may be arranged as desired about the frame or truck 12. An appropriate platform for the apparatus operator may be provided as at 229 in Figure 1.

As diagrammatically illustrated in Figure 3, a hydraulic motor 230 of any appropriate design, and comprising the aforementioned propelling mechanism, may be secured to the frame 12 in any appropriate manner to drive a wheel axle 30 through chain 232 that engages appropriate sprockets. This mechanism 230 may include an appropriate form of clutch for disconnecting same for towing the vehicle to the site of the work. The hydraulic motor 230 may be driven by one of the pumps 40 through the extra valve 200 or by another pump that is driven or actuated by the motor 36 through an appropriate control valve.

LEVEL TRANSFER DEVICE

The vehicle 12 may carry chalk line indicator 244 (see Figure 2) to help in transferring the proper grade to the track rails and track ties. In the illustrated embodiment, indicator 244, which cooperates with chalk line 240, is

hinged, as at 246, to a suitable supporting bar 248, fixed to channel member 57 so that it may be pivoted out of the way when the frame or truck 12 is moved from place to place. Appropriate hooking devices may be provided to secure it in inoperative position.

METHOD OF SHIFTING TIES

The tie shifting operation in accordance with my invention is carried out as follows. After the desired track grade has been determined and a chalk line 240 (see Figure 2) erected, the track spikes 241 at the rail joints are removed and the rails are jacked to the proper elevation at the same time raising or partially raising the unspiked ties. Most of the ties will then hang from the rails, depending from the spikes, the latter being at least partially withdrawn from the ties in most instances. The three right hand ties of Figure 1 show several possible positions, the rail gripping spikes of the tie shown gripped by the machine being completely removed.

After the track rails are jacked to the proper elevation, the truck or frame 12 is moved over the first tie to be moved. As the first tie to be moved is shifted laterally of the track, since, in accordance with my invention, it is entirely removed to make room for succeeding ties to be shifted, it is unspiked and the truck or frame 12 is positioned so that one of the rail clamping devices is positioned above this first tie. The so positioned clamping device 16 is then employed to remove the first tie in the manner generally indicated in Figure 6, wherein a portable spud 250 of any desired shape is applied between one of the studs 145 of movable structure 136 and the tie. By drawing the piston rod 165 of the ram 132 to the right of Figure 6, the tie to be removed may be forced laterally of the track. Of course, several successive operations of the ram 132 are required to completely remove the tie. Some of the ballast may be removed from around the end of the tie to expedite removal, if necessary.

The truck or frame 12 is then moved to the position wherein tie grippers 14 are approximately positioned over the next tie, which is the first tie to actually be shifted, and the valves for controlling rams 132 are actuated to apply rail clamping devices 16 to the rails. The tie engaging members 90 and 92 are separated by manipulating the appropriate valves 200 to actuate cylinders 118 on both sides of the machine and then the valves for actuating rams 114 are manipulated to vertically align tie engaging members 90 and 92 with the tie that is to be shifted. Thereupon, the tie engaging members are lowered into the ballast about the tie to be shifted by actuating the rams 110. After rams 118 have been actuated to force members 92 against the tie to clamp the tie in the grippers, ram 110 are again actuated to raise the tie to the underside of the track rails. This positions the tie above its former position in the ballast, but leaves a pocket in the ballast similar to the pocket that was formed by removing the first tie. The tie is then shifted to its new seat by actuating rams 114 to force same against the ballast to a position intermediate the two pockets, the ballast that is displaced by this action falling into the pocket that was formed by removing the first tie. Rams 118 are then actuated to release the tie and then rams 110 are actuated to raise the members 90 and 92. The tie grippers 90 and 92 are then shifted to the next tie that is to be shifted and the cycle is repeated, the clamping devices 16 being released to permit movement of the vehicle 12 as required by the progress of the tie shifting operation, and then reapplied to the rails.

The order of shifting is illustrated in Figure 1, wherein the ballast 300 displaced by the shifted ties 20 is shown in the pockets 302 formed by shifting the preceding ties (at the left hand side of the figure). Tie plates 304 remain in their normal positions and are not affected by the tie shifting operation. As the machine passes away from the ties that have been shifted, rail spikes 241

7
that have been removed at the joints and elsewhere as necessary are reapplied to the ties in any convenient manner and the other spikes are retightened. Of course, under the track conditions described, the vehicle moves to the right of Figure 1 during the tie shifting procedure.

It may be mentioned that forcing the individual ties against the ballast in shifting them effectively packs the ballast underneath them, which substantially eliminates the need for tamping, or at the very least reduces its need to a bare minimum.

In instances where the ballast between ties, before they are shifted, is deep enough adjacent the center of the track so that the tie after it is shifted would rest on ballast at the center of the track, the rake device 18 is employed to scratch a shallow trench adjacent the center of the track before the tie is shifted. This precludes the possibility of a tie resting on the ballast at the center of the track when it is shifted, which would result in a tie fracture at its center when a load is applied to the track. The rake 170 is raised and lowered by actuating ram 172 by manipulation of its valve 200, and the rake is moved back and forth by actuating rams 114. Ordinarily the beam 174 extends crosswise of the track, rather than in the inclined position of Figure 3.

If the raise in grade is such that new ballast is required, it may be dumped in place before the ties are shifted.

When all the ties that are to be shifted have been moved, the tie that was first removed (or a new tie) may be placed in the ballast between the last tie shifted and the tie next to it. This may be done in any conventional manner.

Skewed ties are easily shifted to correct alignment with the track, either during a tie shifting operation, or independently of a tie shifting operation. This is done by first gripping the skewed tie with the tie grippers 14 and drawing the tie up tight against the rails, after which which the rams 114 on each side of the machine can be independently operated to shift the ends of the skewed tie as necessary to straighten it out. Of course, the skewed tie if located at a rail joint is unspiked before being straightened.

It may be added that the tapered tie engaging ends of tie gripping members 90 and 92 facilitate the penetration of the ballast that is required for them to adequately grip the ties. Projections 96 of the members 90 and 92 merely implement the gripping action applied to the ties, and do not interfere with raising of the grippers after the tie has been released.

It will thus be seen that I have provided a method and machine for shifting track ties which substantially eliminates the need for tamping. My method and machine also reduce new ballast requirements to a minimum. I have found that in using my method and machine a tie shifting operation can be accomplished with six men rather than the relatively large number of men that has been required heretofore. In an embodiment of the invention that has proved highly successful, a hydraulic two-way double acting valve made by Blackhawk Manufacturing Company of Milwaukee, Wisconsin, was employed to perform the functions of the individual valves 200. Pumps 40 took the form of six cylinder wobble pumps made by the same company. A 24 horsepower gasoline engine was employed to operate the pumps.

The foregoing description and the drawings are given merely to explain and illustrate my invention and the manner in which it may be performed, and the invention is not to be limited thereto, except in so far as the appended claims are so limited since those skilled in the art who have my disclosure before them will be able to make modifications and variations therein without departing from the scope of the invention.

I claim:

1. In a track surfacing machine of the type used for carrying tie gripper apparatus for raising and shifting ties in a railroad track, said machine comprising a wheeled

8
frame having a transversely extending support member, a pair of pendently mounted clamp bars mounted on said support member above and straddling one of the rails of said track, one of said bars being mounted in a frame fixed to said wheeled frame and the other of said bars being mounted in a frame movable longitudinally along said support member, cam follower means carried by each of said bars, cam means carried by each of said bar frames for engagement with the cam follower means

5 of the other bar respectively, said cam means each including cam surfaces shaped to raise and lower the respective bars between positions in horizontal alignment with the track rail and positions above the track rail as said movable frame is moved away and toward, respectively, 10 said fixed frame, and ram means for moving said movable frame longitudinally of said support member and transversely of the track, whereby said clamp bars are simultaneously lowered and brought into engagement with the track rail to clamp said wheeled frame to the 15 track when said movable frame is moved toward said fixed frame, and said clamp bars are simultaneously separated and raised to release the wheeled frame from the track when said movable frame is moved away from said fixed frame.

2. The method of shifting track ties in a length of track that is to be raised from an old to a new grade which includes the steps of: jacking the track rails along said length of track to the new grade, removing a track tie adjacent one end of said length of track to form a pocket

30 in the track ballast, lifting the next tie of said length of track adjacent the pocket into contact with the underside of the track rails and then forcing the tie against the ballast between it and the pocket to a position intermediate the pocket and the second mentioned tie's prior 35 location, thereby displacing the ballast toward and into the pocket, lifting the next succeeding tie of said length of track into contact with the underside of the track rails, forcing said next succeeding tie against the ballast between it and the second mentioned tie to a position intermediate the pocket formed by shifting the second mentioned tie and the prior location of the said next succeeding tie, thereby displacing the ballast toward and into the second mentioned pocket, and shifting subsequent ties across said length of track in like manner.

45 3. A railroad car adapted to move and manipulate ties of a railroad track comprising in combination a rigid frame, wheeled axles supporting the frame and adapted to ride on opposed rails of said track, tie-gripping members mounted on opposite sides of said frame intermediate

50 said wheeled axles and outboard of said rails, means for independently moving the tie-gripping members on each side of the frame both vertically and longitudinally of the frame to perform tie-gripping functions, and rail-gripping means mounted on the frame at diametrically opposed corners thereof for clamping the frame to both rails of 55 said track.
